INDICATING CONTROL MEANS FOR RADIO RECEIVING APPARATUS AND THE LIKE

Frederick L. Creager, Merchantsville, N. J., assignor to Radio Corporation of America, a corporation of Delaware

Application August 28, 1931. Serial No. 559,906

13 Claims. (Cl. 116—124.1)

The present invention relates to indicating control means for radio receiving apparatus and the like. More particularly, it relates to indicating control means of the above character having a fixed translucent dial of the "full vision" type and a movable indicator associated therewith.

It is an object of the present invention to provide improved indicating control means having a full vision translucent dial and illuminated indicating means of simple construction, which prevents glare in the illumination of the dial, but which is readily adapted to provide a desired range of illumination of the dial in addition to its indicating function.

15 The invention will be better understood from the following description when taken in connection with the accompanying drawing, and its scope will be pointed out in the appended claims.

In the drawing, Fig. 1 is a view in perspective and partly in section, on a reduced scale, of indicating control means embodying the invention, as applied to the tuning control means of a radio apparatus; Fig. 2 is a cross-sectional view, on an enlarged scale, of the indicating control means shown in Fig. 1; Fig. 3 is a fragmentary view, in perspective, of a modification of the indicating means of Figs. 1 and 2, on the same scale as Fig. 1; and Fig. 4 is a view in perspective and on the same scale as Fig. 2, showing a further modification of a portion of the indicating means of Figs. 1 and 2.

Referring to Figs. 1 and 2, 5 is a portion of the housing or front panel of a radio apparatus having a tuning control shaft 6 which is operated from the front of the panel by a suitable operating knob 7.

In the present example the knob is mounted upon a shaft or roller 8 carried by one end of a lever arm 9 and is connected thereby with the tuning control shaft 6. The shaft 8 is held in frictional contact with a fixed track 10 by a spring pressed roller 11, whereby the lever is caused to move in one direction or the other to actuate the control shaft 6 as the knob 7 is rotated. This control arrangement represents any suitable operating means for the control shaft 6 through the medium of a panel knob.

Associated with the knob 7 is a curved, translucent dial member 12 which forms a closure means for a window 13 in the panel front. In the present example the window is provided in a suitable escutcheon plate 14 for holding the curved dial member in conjunction with the panel 5, which is flat. The shaft 8 projects through a slot 15 in the escutcheon plate 14,

directly below the window 13, whereby the free end of the lever and the control knob 7 may move along the dial member.

A small electric lamp 16 is arranged to be closely associated with the dial member 12 at 60 the rear thereof and to move in response to movement of the control shaft 6. In the present example and as a preferred arrangement, the lamp is arranged to be mounted directly upon the free end of the lever 9, as indicated, 65 whereby it is directly connected with the operating means for the control shaft 6, and moves with the control knob 7.

The lamp is mounted upon an offset portion or platform surface 17 provided on the free 70 end of the lever 9 at the rear of and adjacent to the dial. The lamp is enclosed in a shield or hood 18 having a flat surface 19 arranged in parallel relation to the rear surface of the dial member 12 and spaced from it only sufficiently 75 to permit free operating movement of the hood along the dial member in response to movement of the tuning control means.

The V shaped opening or aperture 20 is provided in the surface 19 whereby a beam of 80 light from the lamp 16 may be projected through the opening onto the dial member to provide an illuminated image of the opening as an indicating means substantially as shown in Fig. 1.

It will be noted, in Fig. 2, that the distance 85 between the surface 19 and the dial member 12 is very short, so that the rays of light from the opening 20 are not permitted to diffuse and to illuminate the scale with an undesirable glare, while at the same time a clearly defined, sharp 90 image is obtained. The lamp is otherwise in all directions entirely shrouded or covered by the hood 18, whereby it is prevented from projecting an illuminating glare upon the dial member. For this reason the hood is preferably of sheet 95 metal or other opaque material whereby the direct, unshielded rays from the lamp are confined and projected directly only through the aperture 20.

The hood is removable for replacing the lamp and for other purposes hereinafter to be described, and to this end is attachably mounted in a shallow, rectangular, sheet metal base member 21 which is secured to the surface 17 of the operating arm in a position to receive and hold the hood 18, as indicated, close to the dial member. The hood is of relatively small dimensions having an interior of only sufficient size 100 to enclose the lamp and its supporting means, 110

whereby it is adapted to move along the dial member in close relation thereto.

The lamp socket is so located that it holds the lamp in the position shown in Fig. 2 with its filament substantially in alignment with the aperture 20 for a maximum illumination of the image on the dial member.

The lamp is provided with a socket 22 which is supported by a bracket 23 secured to the interior of the base member 21. The bracket 23 is insulated from the socket terminals 24 by suitable spacing washers 25. A strip of insulating material 26 is also interposed between the lower terminal 24 and the bottom of the base member 21.

Suitable supply leads 27 for the lamp are connected with the terminals 24 and are carried through the rear wall of the hood through an opening 28 provided by cooperating notches in the hood and its base. The leads are then carried along the lever 9 in retaining loops 29 and are connected with a potential source (not shown) in the apparatus.

From the foregoing description, it will be seen that an indication of the position of the tuning element or control shaft 6 is provided by an illuminated indicator without the usual glare or unnecessary illumination of the dial member. The indicating lamp is placed in close relation to the dial member, at a point for efficient illumination of the indicating area, and is arranged to move along the dial member with the indicating opening in close spaced relation to the dial.

The lamp is completely enclosed by the hood while, at the same time, it is easily accessible by removing the hood from its base member. The indicating means is small and compact, and occupies very little space at the rear of the dial member while, at the same time, it is protected since it is at the rear of the dial, and within the housing of the apparatus.

In certain types of apparatus, it may be desirable to provide a plurality of scales, as indicated in Fig. 3 at 30 and 31, on the dial member 12 and means for utilizing either of the scales, selectively, corresponding to differing conditions of operation of the apparatus, such as short wave and long wave operation for example.

The selective indication in connection with either of the two scales shown, may be provided as indicated, by an additional aperture or opening 32 in a face of the hood 18 opposite to that face in which the aperture or opening 20 is provided.

In the case of V shaped notches as indicating apertures the direction of the indicating point of the V is reversed in the case of the opening 32 so that it will provide an indicating image associated with the upper scale 30 of the dial member 12, while the opening 20 provides the same type of indication in connection with the lower scale 31 as in Figs. 1 and 2.

It will be seen that, by releasing the hood from its base, rotating it 180 degrees and replacing it in its base, the dial indication may be changed from one scale to the other as may be desired in the operation of the apparatus.

The hood 18 may, therefore, not only easily be removed and replaced for the purpose of changing the indicating lamp but it may also be arranged to change the dial indication by the simple addition of other light projecting apertures.

It should be noted, however, that the aper-

tures 20 and 32 are located in opposite faces of the hood whereby when one of them is in use, the other is in a position wherein it does not project light in any direction upon the dial member. It is obvious that hoods of a similar character and with a plurality of faces may be provided to carry out this arrangement with more than two indicating apertures without projecting light upon the dial member while the one of them is in use.

The several apertures should be arranged to align as nearly as possible with the filament of the lamp for sharp definition of the indicating image.

It is also within the scope of my invention to provide a lamp with more than one filament, each filament being arranged to operate in conjunction with the same or different light projecting apertures for selectively projecting an indicating image of one of the apertures upon one of the scales of the dial member.

A further example of a replaceable hood of the above character is shown at 33 in Fig. 4. This hood is of the same general form as the hood 18 and has the surface 19 for the light projecting opening 20 reduced in width to permit sloping the side walls of the hood. The base of the hood is maintained in the same rectangular form to fit within the base member 21. Light projecting louvered openings 34 may then be provided on one or both sides of the hood in the sloping side walls, to cast a diffused light on the scale on one or both sides of the indication provided by the light projected through the opening 20.

With an arrangement of this character the area 19 about the opening 20 provides means for shielding the light in the region of the indicating opening, while the scale receives indirect illumination through the medium of the louvered openings 34. The louvers should be arranged substantially as indicated, so that the scale does not receive direct illumination from the lamp.

It will be obvious that, in an indicating apparatus of the character described, a plurality of interchangeable hoods may be provided whereby the dial member may indirectly be illuminated to a slight degree on one or both sides of the indicating image, and from a common source of light. In certain installations a single louvered opening on either side of the indicator surface 19 may be sufficient to slightly illuminate the dial member, whereby the scale or scales thereon may be read within a region slightly above and below the indicating image, the indicating image standing out clearly in the darkened area provided by the surface 19.

Although the invention has been shown and described in conjunction with a tuning control means of the lever arm type, it is obvious that it may be applied to other forms of control means for radio apparatus and the like, wherein a full vision translucent dial member is provided, the indicating means being arranged to direct light from the source onto the dial member in a predetermined path.

In the present preferred embodiment, the indicating lamp is enclosed in a hood or container having a surface provided with a light projecting indicating orifice, which surface is arranged to move in close spaced relation to the dial member substantially as shown and described.

The walls of the hood, or shield, for the lamp provide rearwardly extending means for deflecting the rays of the lamp away from the dial member, while the indicating opening in the

front wall of the hood permits certain of the rays from the lamp to be directed onto the dial member in a predetermined path.

I claim as my invention:

5. 1. In an indicating control means for radio apparatus, the combination of a fixed translucent dial member, a movable control element arranged to move along one surface of said dial member, a closed container mounted upon said movable control element to move therewith and having a surface located in close spaced relation to said surface of the dial member, means providing a light projecting aperture in said surface, and a lamp mounted in said container. 80
10. 2. In indicating control means for radio apparatus, the combination of a fixed translucent dial member, a movable control element arranged to move along one surface of said dial member, a lamp carried by said movable control element, a base member and a detachable hood mounted thereon providing closure means for the lamp, and means providing a light projecting aperture in one of the walls of said hood. 90
15. 3. In indicating control means for a radio apparatus, the combination of a fixed translucent dial member, a movable control element arranged to move along one surface of said dial member, a lamp carried by said movable control element, a base member and a detachable hood mounted thereon providing closure means for the lamp, means providing a light projecting aperture in one of the walls of said hood, and means providing louvered openings in other walls of said hood for the indirect illumination of 100
35 the dial member from said lamp. 105
4. In radio apparatus, the combination with a movable control element therefor, of a translucent dial member, an indicating lamp, means providing a closed container for the lamp, said container being movable along said scale and having a surface arranged to move in close spaced relation to a surface of the dial member, means providing a light projecting indicating aperture in said surface, and means for controlling the movement of said container along said dial member in response to movement of said movable control element. 110
5. In radio apparatus, the combination with a movable control element and a housing having a window therein, of a translucent dial member providing a closure means for said window, means connected with said control element and movable therewith for projecting an illuminated indicating image upon the dial member, said means including a base member connected with said movable control element and movable therewith along said dial member, a lamp mounted on said base member, a movable hood surrounding said lamp and detachably secured to said base member, said base member being located in a position with respect to the dial member such that the one surface of the hood is located in close spaced relation to the dial member, and means providing a light projecting opening in 115
55 said surface. 120
6. In radio apparatus, the combination with a movable control element therefor, of a translucent dial member, an indicating lamp, means providing a hood for the lamp, said hood being movable along said scale and having a pair of oppositely disposed surfaces, means in each of said surfaces providing a light projecting indicating aperture, a base member forming a 125
65 closure means for the hood in which said hood 130
- is detachably mounted, said hood and the base member being provided with cooperating portions whereby the hood may be detachably mounted therein selectively with either the one or the other of said surfaces in close spaced relation to the dial member, and means for controlling the movement of said hood along the dial member in response to movement of said movable control element. 135
7. In indicating control means for radio apparatus, the combination with a movable control element, of a fixed translucent dial member associated therewith, an indicating lamp mounted upon said element to move therewith in close relation to one surface of the dial member, means including a base member and a second member detachably secured thereto providing an enclosure for the lamp, said second named member having a light projecting aperture adapted to be brought into close spaced relation to the dial member when said member is mounted in said base member. 140
8. In indicating control means for radio apparatus, the combination with a movable control element, of a fixed translucent dial member associated therewith, an indicating lamp mounted upon said element to move therewith in close relation to one surface of the dial member, means including a base member and a second member detachably secured thereto providing an enclosure for the lamp, said second named member being adapted to be mounted in the base member in a plurality of differing positions wherein each one of a plurality of its surfaces may selectively be brought into close spaced relation to the dial member, and means providing light projecting apertures in each of said surfaces. 145
9. In indicating control means for radio apparatus and the like, a dial member through which light may be passed, a member movable relatively to said dial member along the rear face thereof, an illuminating element carried by said movable member and arranged to move therewith in close relation to said rear face of the dial member, and a shield movable in unison with the element carrying member interposed between the dial member and said illuminating element, said shield having an opening therein adjacent to the dial member for defining an indicating spot of light from the illuminating element on the dial member, and said shield having rearwardly directed walls for deflecting the side rays of the illuminating element away from the dial member. 150
10. In a device of the character described, a dial scale through which light may be passed, a member movable relatively to said dial scale and carrying an illuminating element arranged to direct a beam of light onto the rear side of said scale, and a shield movable in unison with the element-carrying member interposed between the scale and said illuminating element and having an opening therein for defining a spot of light projectible onto said scale, said shield having rearwardly-directed side wings for deflecting the side rays of the illuminating element away from the dial scale. 155
11. In a device of the character described, a dial scale through which light may be passed, a member movable relatively to said dial scale to assume different set positions, a lamp mounted on said member to traverse the rear side of the dial scale, and means for shielding 160
70
- 75

all but a small portion of the lamp to direct a spot of light against said scale.

12. A dial mechanism having a scale mounted in a fixed position and constructed for illumination through it from the rear side, a lamp supported at the rear side of the dial for movement relative to said dial for illumination thereof, means associated with said lamp for confining the illumination of the dial to an area of such 5 relative size that it forms an indicating mark on the dial, and means operable to move the lamp and the illumination confining means jointly relative to the scale.

13. A dial mechanism having a scale mounted in a fixed position and constructed for illumination through it from the rear side, a light supported at the rear side of the dial for movement relative to said dial for illumination thereof, a hood associated with the light and having an aperture through which a portion only of the scale is illuminated and means operable to move the light relative to said scale. 80
